US0D1086188S

(12) **United States Design Patent** (10) **Patent No.:** **US D1,086,188 S**
(45) **Date of Patent:** **** Jul. 29, 2025**

(54) **DISPLAY PANEL WITH GRAPHICAL USER INTERFACE**

(71) Applicant: **ELECTRONICS AND TELECOMMUNICATIONS RESEARCH INSTITUTE**, Daejeon (KR)

(72) Inventor: **Jeyoun Dong**, Daejeon (KR)

(73) Assignee: **Electronics and Telecommunications Research Institute**, Daejeon (KR)

(**) Term: **15 Years**

(21) Appl. No.: **29/933,611**

(22) Filed: **Mar. 20, 2024**

(30) **Foreign Application Priority Data**

Jan. 5, 2024 (KR) 30-2024-0000686

(51) **LOC (15) Cl.** **14-04**

(52) **U.S. Cl.**

USPC **D14/485**

(58) **Field of Classification Search**

USPC D14/485-495

CPC G06F 3/048; G06F 3/0481; G06F 3/04812; G06F 3/04815; G06F 3/04817; G06F 3/0482; G06F 3/0483; G06F 3/0484; G06F 3/04842; G06F 3/04845; G06F 3/04847; G06F 3/0485; G06F 3/0486; G06F 3/0487; G06F 3/0488; G06F 3/04883; G06F 3/04886; G06F 3/0489; G06F 3/04892; G06F 3/04895; G06F 3/04897

(57) **CLAIM**

The ornamental design for a display panel with graphical user interface as shown and described.

DESCRIPTION

The FIGURE is a front view of a display panel with graphical user interface showing my new design.

The dashed broken lines illustrate a display panel and form no part of the claimed design.

1 Claim, 1 Drawing Sheet
